Filed Sept. 10, 1971, Ser. No. 179,602

Term of patent 14 years

Int. Cl. D7—05

U.S. Cl. D7—178

FIG. 1 is a perspective view of a net fabric scouring pad showing my new design;

FIG. 2 is a side elevation thereof;

FIG. 3 is a top plan view thereof;

FIG. 4 is a bottom plan view thereof; and

FIG. 5 is a second side elevational view thereof.

The cross-hatching is partially shown on the pad for convenience of illustration, it being understood that the cross hatching is continuous over the pad's surface.

I claim:

The ornamental design for a net fabric scouring pad, as shown and described.
